UNITED STATES PATENT OFFICE.

GEORGE F. BAITZ, OF PHILADELPHIA, PENNSYLVANIA.

COMBINATION DISPLAY AND VENDING DEVICE.

Application filed May 12, 1921. Serial No. 468,850.

To all whom it may concern:

Be it known that I, GEORGE F. BAITZ, a citizen of the United States, residing at Philadelphia, in the county of Philadelphia and 5 State of Pennsylvania, have invented certain new and useful Improvements in Combination Display and Vending Devices, of which the following is a specification.

One object of my invention is to provide 10 an improved device of novel construction which can be conveniently used for display and vending purposes. For example my improved device is well adapted for displaying and vending such articles as souvenir post- 15 cards and packets of garden seeds.

Another object is to include in my improved device a wheel with means for holding 20 said articles thereon so that any of said articles can be moved into view by turning said wheel so that they can be conveniently inspected and easily removed.

A further object is to construct my invention so that it can be kept and operated in a comparatively small space.

25 These objects, and other advantageous end which will be described hereinafter, I attain in the following manner, reference being had to the accompanying drawings in which

30 Figure 1 is a side elevation of my improved device,

Figure 2 is an end elevation of Figure 1,
Figure 3 is a section taken on the line 3—3 of Figure 1,

35 Figure 4 is an enlarged fragmentary section taken on the line 4—4 of Figure 1,

Figure 5 is an enlarged top plan view of a portion of said wheel,

Figure 6 is a view showing the opposite 40 side of Figure 5,

Figure 7 is a fragmentary top plan view of the base showing various positions into which the legs can be moved, and

45 Figure 8 is a view of the same general character as shown in Figure 5 illustrating a different arrangement of the retaining means.

Referring to the drawings, 10 represents a 50 frame having parallel opposite sides to which are pivotally connected legs 11; said legs being adapted to swing into various positions as shown in Figure 7 so that the device may be stood in positions adjacent other articles without interference by the legs.

55 The frame 10 and legs 11 constitute a base and serve to support a drawer 12. The

frame 10 has a glass top 13 so that the contents of the drawer is visible through the glass top 13. This drawer can be used for storing a reserve supply of articles and its 60 use will be more thoroughly comprehended from the following description.

Two posts or standards 14 have their lower ends fitting within the frame 10 and are secured by screws 15 as shown in Figure 65 1. These posts 14 adjacent their tops support a horizontal axle 16. A wheel 17 includes a rim 18 which is semi-circular in cross section; the curved part being inwardly disposed. Spokes 19 are secured to 70 the rim 18 and overlap each other in the form of overlap joints and through these joints extends the axle 16. A number of radially disposed partitions 20 is spaced apart around the periphery of the rim 18; 75 said partitions between their opposite ends being cut out as shown at 21 in Figure 3 to embrace the rim 18 so that parts of the partitions extend beyond opposite sides of 80 said rim; the inner edge portions 22 of said partitions being located closer to the axis of the wheel than is the peripheral surface 23 of said rim.

Flat plates or boards 24 are secured to the peripheral surface 23 of the rim preferably 85 by screws 25; said plates having their opposite edges abutting the opposite sides of the partitions 20 at positions between their inner edges 22 and outer edges 26 as shown in Figure 1. Thus outer channels are provided between the opposite side surfaces of the partitions; said plates or boards serving as a base for said channels and it is within these channels that articles which are to be displayed and vended are positioned, such for 90 example as shown at 27 in Figure 4.

I preferably provide a ring or hoop 28 which entirely encircles the wheel; said ring fitting within notches 29 in the outer edges 95 26 of the partitions and adjacent one end of the channels. At a position of the wheel opposite the hoop 28 I provide spring clips 30 adapted to engage and hold the articles 100 27 within the channels and if desired any of the articles 27, which may be postcards, can be slipped out of the channels under the hoop 28 by merely sliding the articles lengthwise of the channels. It will also be noted that the portions of the partitions between the cut out parts 21 and the ends of 105 26 said partitions form inner channels at either side of the rim 18 and the same plates or

- boards form the inner parts of the channels so that said inner channels can be used for containing articles such for example as packets of garden seeds as shown at 31 in Figure 4. The springs 32 are secured between their ends to the inner surface of the rim and the opposite free ends are adapted to hold the articles 31 against the inner surfaces of the plates 24.
- 10 I may also attach plates 33 to the spokes 19 as shown in Figure 1; said plates having flanges 34 and spring clips 35. Thus the wheel is capable of supporting articles on its outside and inside and a person standing adjacent the wheel can inspect any of the articles by rotating the wheel into a convenient position so as to bring the desired articles into close view and if it is desired to purchase any of the articles they 15 can be readily withdrawn as is obvious from the construction above described. The drawer 12 serves to hold the reserve articles so that when any of the articles in the wheel have been sold, they can be replaced 20 from the stock contained in the drawer 12.
- In Figure 8, I have shown a slight modification where instead of having the hoop 28, I provide separate clips 30^a which may be used if desired or if desired these clips 25 30^a may be eliminated and the clips 30 made sufficiently strong to hold the articles during the rotation of the wheel. By having the legs adjustable as previously stated, they can be moved into positions to accommodate 30 any other articles such for example as if the device is placed upon a counter or on the floor near other articles and it is desired to conserve the floor space.
- While I have described my invention as 35 taking a particular form, it will be understood that the various parts of my invention may be changed without departing from the spirit thereof, and hence I do not limit myself to the precise construction set forth, but consider that I am at liberty to make such changes and alterations as fairly come within the scope of the appended claims.
- Having thus described my invention, what 40 I claim as new and desire to secure by Letters Patent is:—
1. A device of the character described including a wheel, partitions spaced apart on the rim of the wheel; and members 45 extending between said partitions and located between the inner and outer edges of said partitions to provide inwardly and outwardly depressed channels; substantially as described.
2. A device of the character described including a wheel; partitions spaced apart and projecting from the rim of the wheel, said partitions having parts cut out so as to embrace said rim; and means interposed be-
- tween said partitions whereby inner and outer channels are provided.
3. A device of the character described including a wheel; partitions spaced apart and projecting from the rim of the wheel, said partitions having parts cut out so as to embrace said rim; means interposed between said partitions whereby inner and outer channels are provided; and spring clips secured to said rim and having free ends adapted to hold articles in said inner channels at positions at opposite sides of the rim.
4. A device of the character described including a wheel mounted to turn on a horizontal axis and having radial partitions spaced apart providing open channels; a hoop encircling said partitions; and spring clips in said channels opposite said hoop for holding articles for display in said channels, substantially as described.
5. A combination display and vending device including a wheel having a rim semicircular in cross section; partitions spaced about said rim and having notched out portions for the reception of the rim; and plates carried by the peripheral surface of the rim and abutting the opposite sides of the partitions, said partitions and said plates forming channels into which articles for display are placed.
6. A combination display and vending device including a wheel having a rim semicircular in cross section; partitions spaced about said rim and having notched out portions for the reception of the rim; plates carried by the peripheral surface of the rim and abutting the opposite sides of the partitions, said partitions and said plates forming channels into which articles for display are placed; and means for holding the articles in said channels when the wheel is rotated.
7. A device of the character described including a wheel having a rim; partitions spaced apart around said rim, said partitions embracing said rim, and means interposed between said partitions and dividing the same into inner and outer channels.
8. A device of the character described including a wheel; partitions spaced apart and projecting from the rim of the wheel, said partitions having parts cut out so as to embrace said rim; means interposed between said partitions whereby inner and outer channels are provided, and means for detachably holding articles in said channels, said channels being open at their ends.
- In testimony whereof I have signed my name to this specification in the presence of two subscribing witnesses.
- GEORGE F. BAITZ.
